FEEDER AND IMPRESSION CYLINDER CONTROL FOR PRINTING PRESSES

John F. Banthin, Bridgeport, Conn.

Application May 1, 1947, Serial No. 745,262

5 Claims. (Cl. 101—284)

1

This invention relates to new and useful improvements in printing presses and has particular relation to a pneumatic valve system for controlling the feeding of paper sheets to a printing press and simultaneously controlling the impression cylinder for the "on" and "off" positions.

An object of the invention is to provide a press including a system or means whereby on failure of the vacuum suckers to deliver a sheet of paper to the impression cylinder, the latter will be held against movement toward the type or toward "on" position whereby application of ink to the cylinder blanket is prevented.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a side elevational view showing the present mechanism applied to a press, the parts being in position for the vacuum suckers to remove a sheet from a stack;

Fig. 2 is a similar view but showing the parts positioned as when a sheet has just been delivered to the impression cylinder;

Fig. 3 is a similar view showing the parts with the impression cylinder locked in "off" position;

Fig. 4 is a transverse sectional view taken as along the line 4—4 of Fig. 1, the stack of sheets being omitted; and

Fig. 5 is an enlarged side elevational view showing details of construction.

Referring in detail to the drawings, at 10 is generally indicated a printing press, but a portion of the same being shown, the type bed and the like being no part of the present invention and being omitted. The press 10 comprises a cast base or frame 11 on which the various parts are mounted, such parts including an impression cylinder 12, mounted as between brackets 13, and a feeder table or support 14 for a stack of paper, cardboard or the like 15 to be printed. The feeder table is equipped with front guides 15a and with other required guides (not shown), all as is usual in the art.

The present invention is concerned with a system or means for retaining the impression cylinder 12 in elevated or "off" position at such times as the delivery mechanism may fail to deliver a

2

piece of paper or the like during operation of the press. In the normal cycle of operation of the press, a feeder mechanism delivers a piece of paper to the impression cylinder where it is gripped as the cylinder moves downwardly to have the paper engaged by the type when the latter moves under the cylinder during each cycle of the machine's operation. Thus, when the feeder mechanism fails to deliver a sheet of paper and the machine proceeds through its normal cycle, the type will engage the impression blanket on the cylinder inking such blanket and thereafter the next sheet of paper will have an offset transfer on its reverse side as it takes up ink from the impression blanket.

To avoid this, the impression blanket must be changed. According to the present invention, when during a cycle of the machine's operation the feeder mechanism fails to deliver a sheet to the impression cylinder, the latter is retained in its upper or inoperative or "off" position and its blanket will not be engaged by the type as the type bed is carried under the cylinder.

The means of the invention is controlled by 25 the suction used in the feeder mechanism. Such mechanism, as here shown, includes feeder brackets 16 and a pair of arms 17 and 18 mounted on horizontal pivots 19 in the side portions 20 of the frame 11. At their upper ends arms 17 and 18 are connected by a manifold 21 which applies a vacuum or suction to suckers 22 through tubular flexible connections 23. The suction is applied to the manifold from a pump 24 driven by a motor 25 as through a belt 26 and pulley 27. From the pump, a pipe 28 leads to a T-fitting 29, one branch of which is connected with a vacuum gauge 30 and to the other branch of which is connected a pipe or tube 31 leading to a valve body 32 mounted on one of the frame sides 20.

From this valve body 32, a pipe 33 leads to a valve body 34. Valve body 32 is hollow having a passage 35 opening through its upper side and also communicating with the pipes 31 and 33. Normally, a pivotally mounted valve lid 36 closes the open upper side of the valve body 32 to prevent breaking of the vacuum. Within the valve body 34 is a plunger 37 held in an inner position when a vacuum is applied to said valve body and which plunger at its lower end carries a head 38 provided with a pin 39 operating between the jaws of a bifurcated arm portion 40 of a substantially L-shaped catch device 41.

Device 41 is pivoted as at 42 and has its other arm 43 notched whereby to provide it with a

shoulder 44, the purpose of which will later appear. The pump 24 is equipped with a pet cock 45 while the valve body 34 is equipped with a similar device 46. A trip lever for the lid 36 is designated 47 and the same is mounted on a pivot 48 located toward one end of said trip lever whereby the same is eccentrically mounted. The inner or longer end portion 49 of this lever 47 normally underlies the extended portion of the lid 36 and is normally retained in a lower position as by a spring 47a on the pivot 48 (see Fig. 4) whereby the lid is closed as in Figs. 1 and 3.

Extending upwardly from a coupling 59 located in the line 33 is a tube of rubber or other flexible material 51 which at its upper end communicates with the interior of the manifold 21. At spaced points, this tube is clipped to the arm 17 as at 52. From the above, it will be understood that when the pump 24 is operating, a suction is created through the line 31 and within the valve bodies 32 and 34 and through the pipe or tube 51 and the manifold 21 to the suckers 22. Suction is also applied to the inner end of the plunger 37 and when the lid 36 is closed and the suckers are holding a piece of paper, the suction is sufficient to maintain the plunger 37 in an inner position.

The manifold 21 is actually supported by arms 53 of levers which are pivoted intermediate of their ends as at 54 to the outer ends of the arms 17 and 18. Each of these levers includes a second arm 55 to the rear end of which are pivotally attached the upper ends of rods 56, which rods also pass through guide lugs 57. Coil springs 58 on the respective rods between one lug 57 and a shoulder or nut 59 and normally bearing against said nut, tend to rock the pivoted levers whereby their arms 53 are rocked downwardly or clockwise about the pivots 54.

Extensions 60 from the feeder brackets 60 pivotally mount a feed plate 61 at its ends carrying rigid forwardly projecting extensions 62 which at their outer ends, in positions over the cylinder 12, support head stops 63. The pivot for the feed plate 61 is designated 61a. Extensions 60 have pivoted to their outer ends short arms 64 at least one of which is pivotally connected to the upper end of a link 65, the lower end of which is pivoted to one arm of a bell crank 66. This bell crank is operated by means (not shown) conventional in the art, for rocking the arms 64 to have a roller 67 thereon engage the feed plate 61 and elevate it and thereby the head stops 63 as from the position of Fig. 1 to that of Fig. 3.

The lower end of the feeder arm 17 is provided with a crank-like extension 17a, to the outer end of which is pivotally connected a link 68. The lower end of said link is pivotally connected to an arm 69 of a rocker 70 pivoted intermediate its ends as at 71 and at the outer end of an arm 72 carrying a roller 73 located in the same groove 74 of a cam 75. Cam 75 is mounted on a shaft 76 also mounting a gear 77 and which gear is meshed with a gear 78 on a shaft 79 carrying a cam 80.

These gears 77 and 78 are driven in any suitable manner (not shown) and as the cam 75 rotates, the rocker arm 70 is rocked up and down about the shaft 71 and thereby through the link 68 and crank arm 17a, causes shifting of the feeder mechanism and particularly the suckers 22, from the pick up or loading position of Fig. 1 to the drop off position of Fig. 2 and then back.

During the forward movement of the suckers, a sheet of paper is carried from the stack 15 and at the end of the forward movement is delivered to the grippers of the impression cylinder 12.

5 The impression cylinder 12 is mounted on an eccentric 81 located about a shaft 82 mounting a gear 83 which is driven in a suitable manner (not shown) whereby the impression cylinder is driven in synchronism with the movement of the 10 type bed (not shown). Clearly, turning of the eccentric 81 in one direction or the other will raise or lower the impression cylinder 12 and when the latter is raised, it will be in "off" position spaced from the type bed. When the cylinder 15 is lowered, it is in "on" position and then carries a sheet of paper and presses the latter against the type as the type bed is moved under the cylinder whereby to print on the sheet.

After the type bed passes under the cylinder 20 and makes its impression, the cylinder is raised and the type bed passed back to its normal position. The eccentric 81 is fast to an arm 84 to the outer end of which is pivotally connected a link 85. Said link is connected to a similar link 25 86 by means of a rod 87, and link 86 is pivoted at 88 to one branch of a cylinder trip arm 89 which latter is pivoted toward one end as at 90. Cylinder trip arm 89 includes a latching extension 91 designed to cooperate with the shoulder 30 44 of the L-shaped catch device 41 previously described.

Pivotedly connected with the trip arm 89 is a link 92 to which is connected a rod 93 also passing through a pivoted guide 94 mounted on the machine frame 11. A coil spring 95 is mounted on this rod 93 between the guide 94 and a collar 96 and is constantly thrusting against the collar tending to rock the trip arm 89 in a clock-wise direction about the pivot 90. A link 97 is pivoted 49 at 98 to the trip arm 89 and at 99 to an arm 100 of a bell crank lever 101, which latter is pivoted at 102 and includes an arm 103 carrying a roller 104 bearing against the cam 80. Clearly, the link 97 is connected with the trip arm 89 in advance of the pivot 90 of the latter. Therefore, on certain movement of the link 97, as toward the left in Figs. 1-3, the trip arm 89 is rocked from the position of Fig. 1 to that of Fig. 3.

50 Mounted on the arm 17 of the feeder mechanism is a stud 105 through which is threadedly adjustable a screw 106 designed to engage the trip lever 47 and rock the same as to the position of Figs. 2 and 5 so as to tilt the lid 36 of the valve body 32 and break and maintain broken the vacuum in the various parts of the system. It will be apparent that the screw 106 is movable with the transfer mechanism from the position of Fig. 1 through to the position of Fig. 2 in which latter position it has rocked the trip lever 47 and caused lifting of the lid 36 of the valve body 32 opening the suction system to atmospheric pressure. Here it is noted that owing to the eccentric mounting of the trip lever 47 a mechanical advantage is obtained whereby opening movement of the lid 36 is a rapid movement.

When the apparatus is in use, the vacuum gauge 30 serves to indicate and adjust the relative vacuum needed for different kinds and weights of paper to be fed by the feeder mechanism. The pet cock 45 at the vacuum pump and the pet cock 46 at the valve body 34 are used only occasionally as may be required by adjusting the vacuum at the suckers 22 and the plunger 37 to compensate for the difference in weight of 70 the paper as when feeding very light tissue or

onion skin paper in the feeder at one time and heavy cardboard at another time.

With the above understanding, assuming that adjustments have been made whereby the proper degree of vacuum will be applied for handling of the stock 15 to be printed upon, the machine is started. For the present, we will assume that the operation will start from the position of Fig. 1. There the suckers 22 will pick up the top sheet of paper (customarily means are employed for providing a blast of air against the front edges of the stock in line parallel with the stock so as to separate the upper sheets from the pile). It will be understood that the full suction pressure will be applied through the suckers since the valve lid 36 is closed.

As the cam 75 rotates and rocks the arm 70, the feeder mechanism carrying the sheet of paper is rocked in a clockwise direction carrying the sheet of paper from the stock pile to the impression cylinder. While the sheet of paper is retained by the suckers, the vacuum remains sealed in the described pipe line and the sheet is carried forward to the head stops 63. The leading edge of the sheet is just ahead of the suckers and the edge of the paper is brought against the head stops.

At this point, in the movement of the feeder mechanism, the screw 106 engages the short arm of the trip lever 47 and actuates the same to have its long arm engage the extended portion of the valve lid 36 raising the same and thereby breaking the vacuum in the system. Since the screw 106 is mounted directly on the arm 17 of the feeder mechanism, it is possible to make a direct and accurate setting as to the point of release of the sheet by the suckers and such point may be at any desired place forwardly of the head stops 63.

When the lid 36 is raised and the vacuum in the system broken, the vacuum at the suckers is lost and the latter drop the sheet of paper at the head stops. The breaking of the vacuum also allows the plunger 37 to drop in the valve body 34 as from the position of Fig. 1 to that of Fig. 3 permitting of a corresponding movement of the cylinder locking lever or latch device 41. Then in the normal cycle of operation of the machine, the feeder mechanism moves back toward the stock pile and after a very short movement, screw 106 is out of the way and the spring actuated trip lever 47 moves back to normal permitting the valve lid 36 to close. Therefore, when the suckers get back to the stack of paper and engage a sheet, the vacuum is again reestablished in the system and the suckers grip the paper and the plunger 37 is raised and the feeder mechanism carried forwardly to deliver the new sheet of paper to the impression cylinder.

If, for any reason, the sheet of paper is not retained or held by the suckers, as the feeder mechanism moves from the position of Fig. 1 toward the impression cylinder, the vacuum in the system is broken due to the leakage of atmosphere through the suckers. This being true, the plunger 37 in the valve body 34 drops or has dropped to the lower position of Fig. 3. While the cam 75 is operating to move the feeder mechanism as described, the cam 80 acting on the roller 104 also acts on the trip arm 89 and it will be understood that the spring 95 is constantly pressed to shift said trip arm.

During each cycle of operation of the machine, cam 80, as its high point is approached, acting on the roller 104, rocks the bell crank 101 in a counter clockwise direction and through the link

97 forces the trip arm 89 from the position of Fig. 1 to the position of Fig. 3. When these parts are positioned as in Fig. 1, the spring 95 has acted to cause an upward thrust through the rod or bar 5 87 rocking the eccentric 81 and lowering the impression cylinder 12 whereby paper on the cylinder will be engaged by the type.

Then as the high point of the cam rocks the bell crank in a counter clockwise direction the trip arm 89 is rocked also in a counter clockwise direction against the tendency of the spring 95 thereby shifting the eccentric 81 in the opposite direction to raise the impression cylinder as to the position of Fig. 3. As this occurs, the latch portion 91 of the trip arm is carried to a lower position and after the vacuum in the system has been broken, as when the suckers are not carrying a piece of paper, and the plunger 37 has been permitted to drop, the L-shaped locking lever or catch device 41 shifts in such a manner that the latch part 91 enters under the shoulder 44 of the lever whereby the tripping lever 89 is locked down in the position of Fig. 3 with the impression cylinder 12 in its upper or "off" position.

Thus, while under these circumstances the suckers may have failed to deliver a piece of paper to the impression cylinder, the blanket of the latter will not become soiled by ink from the type since the impression cylinder is locked in this upper or "off" position. In the normal use of the machine, when the suckers drop the sheet against the head stops, the trip arm 89 has already moved to a position wherein its latch portion 91 is above a position wherein it may be engaged by the catch device 41. At such time, the printing cylinder or impression cylinder is in its "on" or impression position and the sheet of paper is taken by the cylinder grippers (not shown) and revolved with the cylinder for the printing operation. Thereafter, the paper is taken by the delivery grippers (not shown) and delivered to a pile.

With the present mechanism, since the cylinder will be locked in "off" position when the suckers fail to carry a sheet of paper, it will be apparent that the type bed will not accidentally print on the cylinder blanket. Should such happen, the blanket would offset print upon the backs of the next sheets of paper following the accidental operation and thereby spoil the following sheets. Since, with the present mechanism, the impression cylinder will be locked in its "off" or non-printing position whenever the suckers fail to carry a sheet of paper toward the cylinder, no damage to the cylinder blanket will occur and the feeder mechanism will return to the stock pile, pick up a sheet of paper, bring it over to the cylinder and the operations will be carried on as usual.

It will be appreciated that there will be no damage to any part when the impression cylinder is locked in "off" position since the entire movement of the cylinder to "on" or printing position is brought about by operation of the spring 95 and the present locking mechanism merely functions to prevent such spring from functioning when the suckers fail to carry a sheet during their movement toward the impression cylinder.

Having thus set forth the nature of my invention, what I claim is:

1. In a printing press including an impression cylinder movable between "on" and "off" positions and in the former of which the cylinder is positioned to have type impress ink on a sheet carried by the cylinder, vacuum feeder means in-

cluding suckers for moving a sheet from a pile to said cylinder while the latter is in "off" position, eccentric means for raising said cylinder to "off" position and lowering it to "on" position, a pivoted arm, a connection between said arm and said eccentric means, means alternately cam and spring operated for shifting said arm to move said eccentric means and raise the cylinder to off position and lower the cylinder to on position, a latch rigid with said arm and movable in a predetermined path as said arm is alternately moved by the cam and spring means, a system for applying vacuum pressure to said feeder means, a valve body in said system, a second body in said system in series with said valve body, said valve body forming a connection between a vacuum pump and said feeder means at a point in said system inwardly of said second body, said valve body adapted to be opened to atmosphere to break the suction in said system and render said feeder means inoperative, means movable with said feeder means to open said valve body in a predetermined position of said feeder means to break said vacuum and have said feeder means deposit a sheet to be printed and to cause closing of said valve body on return movement of said feeder means, a plunger in said second body and adapted to be held inwardly thereof by suction when said valve is closed and said suckers are holding a piece to be printed upon whereby said system is closed, a pivoted catch connected with said plunger and held in inoperative relation out of the path of movement of said latch when said vacuum system is closed, and held in the spring-urged path of movement of said latch when said vacuum system is open, and said plunger adapted to move outwardly of said second body and permit said catch to move into locking relation in said spring-urged path of movement of said latch when said system is open to atmosphere whereby to lock said cylinder in "off" position on said feeder means moving from the paper pile toward said cylinder without said suckers being sealed by a piece of paper whereby on failure of the feeder means to deliver said paper to the cylinder the same will be held in "off" position during the cycle of the press' operation so that the type of the press may not apply ink to the impression blanket of the cylinder.

2. In a printing press including an impression cylinder movable between "on" and "off" positions and in the former of which the cylinder is positioned to have type impress ink on a sheet carried by the cylinder, vacuum feeder means including suckers for moving a sheet from a pile to said cylinder while the latter is in "off" position, shiftable means for raising said cylinder to "off" position and lowering it to "on" position, a pivoted arm, a connection between said arm and said shiftable means, means alternately cam and spring operated for shifting said arm to shift said shiftable means and raise the cylinder to off position and lower the cylinder to on position, a latch rigid with said arm and movable in a predetermined path as said arm is alternately moved by the cam and spring means, a system for applying vacuum pressure to said feeder means, a valve body in said system, a second body in said system in series with said valve body, said valve body forming a connection between a vacuum pump and said feeder means at a point in said system inwardly of said second body, said valve body adapted to be opened to atmosphere to break the suction in said system and render said feeder means inoperative, means movable with said

feeder means to open said valve body in a predetermined position of said feeder means to break said vacuum and have said feeder means deposit a sheet to be printed and to cause closing of said valve body on return movement of said feeder means, a plunger in said second body and adapted to be held inwardly thereof by suction when said valve is closed and said suckers are holding a piece to be printed upon whereby said system is closed, a pivoted catch connected with said plunger and held in inoperative relation out of the path of movement of said latch when said vacuum system is closed, and held in the spring-urged path of movement of said latch when said vacuum system is open, and said plunger adapted to move outwardly of said second body and permit said catch to move into locking relation in said spring-urged path of movement of said latch when said system is open to atmosphere whereby to lock said cylinder in "off" position on said feeder means moving from the paper pile toward said cylinder without said suckers being sealed by a piece of paper whereby on failure of the feeder means to deliver said paper to the cylinder the same will be held in "off" position during the cycle of the press' operation so that the type of the press may not apply ink to the impression blanket of the cylinder.

3. In a printing press including an impression cylinder movable between "on" and "off" positions and in the former of which the cylinder is positioned to have type impress ink on a sheet carried by the cylinder, vacuum feeder means including suckers for moving a sheet from a pile to said cylinder while the latter is in "off" position, shiftable means for raising said cylinder to "off" position and lowering it to "on" position, a pivoted arm, a connection between said arm and said shiftable means, means alternately cam and spring operated for shifting said arm to shift said shiftable means and raise the cylinder to off position and lower the cylinder to on position, a latch rigid with said arm and movable in a predetermined path as said arm is alternately moved by the cam and spring means, a system for applying vacuum pressure to said feeder means, a body in said system, a plunger in said body and adapted to be held inwardly thereof by suction when said system is closed, a pivoted catch connected with said plunger and held in inoperative relation out of the path of movement of said latch when said vacuum system is closed, and held in the spring-urged path of movement of said latch when said vacuum system is open, and said plunger adapted to move outwardly of said body and permit said latch to move into locking relation in said spring-urged path of movement of said catch when said system is open to atmosphere whereby to lock said cylinder in "off" position on said feeder means moving from the paper pile toward said cylinder without said suckers being sealed by a piece of paper whereby on failure of the feeder means to deliver a sheet of paper to the cylinder the same will be held in "off" position during the cycle of the press' operation so that the type of the press may not apply ink to the impression blanket of the cylinder.

4. In a printing press including a base comprising a frame to have a type bed reciprocated horizontally thereon, a feeder table at one end of said base, an impression cylinder supported by said base over the horizontal path of the type bed, means mounting said cylinder for vertical movements between on and off positions in the former of which the cylinder is positioned to have

type from a type bed being reciprocated on said frame impress ink on a sheet carried by the cylinder and in the latter of which the cylinder is spaced vertically above the type of a type bed being reciprocated on said frame, a vacuum feeder means for shifting a sheet from said feeder table to said cylinder while the latter is in off position, a system for applying vacuum pressure to said feeder means, an eccentric for raising and lowering said cylinder to and from said off and on positions, an arm pivotally connected with said eccentric, a spring means constantly acting on said arm to shift the same longitudinally to rock said eccentric in a direction to shift said cylinder to on position, cam means acting on said arm at a predetermined time during the cycle of operation of the press to shift the same and said eccentric against the tendency of said spring to move said eccentric in the opposite direction and shift said cylinder to off position, a latching extension rigid with said arm, and means movable in one direction in response to the vacuum pressure in said system out of the path of movement of said latching extension and in another direction into the path of movement of said latching extension to lock the same and thereby said arm and cylinder against return from off to on position on failure of vacuum pressure in said system.

5. In a printing press including a base comprising a frame to have a type bed reciprocated horizontally thereon, a feeder table at one end of said base, an impression cylinder supported by said base over the horizontal path of said type bed, means mounting said cylinder for vertical movements between on and off positions in the former of which the cylinder is positioned to have type from a type bed being reciprocated on said frame impress ink on a sheet carried by the cylinder and in the latter of which the cylinder is spaced vertically above the type of a type bed being reciprocated on said frame, a vacuum feeder means for shifting a sheet from said feeder table to said cylinder while the latter is in off po-

30
